UNITED STATES PATENT OFFICE.

LEONARD BAILEY, OF WETHERSFIELD, CONNECTICUT.

DESIGN FOR A FRAME FOR COPYING-PRESSES.

SPECIFICATION forming part of Design No. 33,560, dated November 13, 1900.

Application filed July 13, 1900. Serial No. 23,548. Term of patent 14 years.

To all whom it may concern:

Be it known that I, LEONARD BAILEY, of Wethersfield, Hartford county, Connecticut, have invented and produced a new and original Design for Frames for Copying Presses, which is described in the following specification and is illustrated by the accompanying drawing.

The drawing is a perspective view of the frame of a copying-press, showing my new design.

As shown in said drawing, the leading or material features of my design are the following, viz: the horizontal base 1, which is of general rectangular form, and the two vertical posts or pillars 2, which are duplicates of each other and rise from base 1 near its opposite ends, respectively, and when regarded independently of the arch 3, by which they are united, they are of uniform size and shape from top to bottom and relatively to each other are of uniform cross-section throughout their entire length, the arch 3, which connects the top of posts 2, being flat and horizontal as respects its upper surface and vertical as respects its sides.

The design consists in the configuration and appearance of the article in its entirety and results from the shape and arrangement of the several parts of which the frame is composed.

Having described my invention, I claim as new and desire to secure by Letters Patent—

The design for a frame for a copying-press, as herein shown and described. 35

In testimony whereof I have subscribed my name to this specification in the presence of two subscribing witnesses.

LEONARD BAILEY.
